(Cl. D81—10)

To all whom it may concern:

Be it known that I, Oscar M. Voiles, a citizen of the United States, residing at Royal Oak, in the county of Oakland and State of Michigan, have invented a new, original, and ornamental Design for a Combined Toaster and Hot Plate or Similar Article, of which the following is a specification, reference being had to the accompanying drawing, forming part thereof.

Figure 1 is a perspective view of the combined toaster and hot plate or similar article, in its closed position, showing my new design.

Fig. 2 is a similar perspective view thereof with the side panels in their lowered position.

Fig. 3 is a front elevation thereof with the parts in the position of Fig. 1.

Fig. 4 is an end elevation of the same.

I claim:

The ornamental design for a combined toaster and hot plate or similar article, as shown.

OSCAR M. VOILES.
